UNITED STATES PATENT OFFICE.

MARIAN M. GREEN, OF COUNTY LINE, TENNESSEE.

COMBINED RAILWAY-CHAIR AND CROSS-TIE.

SPECIFICATION forming part of Letters Patent No. 435,221, dated August 26, 1890.

Application filed June 2, 1890. Serial No. 354,066. (No model.)

To all whom it may concern:

Be it known that I, MARIAN M. GREEN, residing at County Line, in the county of Moore and State of Tennessee, have invented a new and useful Combined Railway-Chair and Cross-Tie, of which the following is a specification.

My invention has for its object to provide a combined rail-chair and cross-tie which will possess the necessary elements of strength, durability, and general efficiency; and it consists in the novel arrangement and peculiar combination of parts, all of which will hereinafter be fully described in the annexed specification, and particularly pointed out in the claims, reference being had to the accompanying drawings, in which—

Figure 1 is a top plan view of my improvement. Fig. 2 is a transverse section taken on the line 2 2, Fig. 1; and Fig. 3 is a detail section taken on the line 3 3, Fig. 1.

In the accompanying drawings, A indicates the metallic cross-tie, which is formed in two sections a a' , jointed as at a^2 , preferably by forming the section a with a tongue a^4 , which fits a socket a^3 in the section a' , said sections being held together by means of the connecting-plate B and the bolts b b , as clearly shown in Figs. 1 and 2 of the drawings. By reference to said figures and Fig. 3 it will be seen that I form the cross-tie **H** shape in cross-section, the plate B fitting in the upper socket h , and to each end of said plate is seated the base c of the pillow-blocks C C, said base being formed with dovetailed channels c c' , which fit the upper socket h , the side walls thereof being dovetailed, as shown.

By connecting the pillow-block to the cross-tie in the manner described the same cannot be pulled up away from the tie, and to hold said block from lateral movement I secure the same to the cross-tie by means of the lock-bolts D D, which pass through the extensions C' of the block and through a pair of a series of apertures a^5 a^6 in the tie, as shown.

Upon each of the pillow-blocks C is mounted a chair E, which consists of the base portion e , extended at e e' , and the fixed guide or brace e^2 , which bears against one side of the web of the rail F, an adjustable guide-brace e^3 being provided, which bears against the opposite side of the rail, said brace e^3 being formed

with an extension e^4 , through which and the extensions e e' are passed the securing-bolts G G', which pass down through extensions C' C' on the pillow-block, the extensions e e' and e^4 being provided with additional apertures 10 10, as shown.

From the foregoing description, taken in connection with the drawings, the advantages of my improvement will readily appear. It will be seen that by the said construction I am enabled to lay a solid bearing for the rails in soft or marshy lands, and by forming the cross-tie in the shape shown the hollow bottom will keep the same from sinking in the ground but little farther than the depth of the lower socket as the earth becomes packed therein. The pillow-blocks serve to hold the rails above the surface of the ground or the water in marshy lands.

In laying road-beds with my improvements the cross-tie, the pillow-block, and the chair can be used in marshy sections and the chair and the cross-tie alone used in the dry or hard ground districts; or the tie and the pillow-blocks may be dispensed with and the chairs bolted directly to the ordinary wooden ties, the additional apertures 10 being provided for the spikes.

By providing the tie A with a series of apertures a^5 the same may be readily secured to bridge-timbers, and by dividing said tie, as described, makes it give to the sudden strain or jars caused by rapidly-moving trains, as metal ties, when made in a single piece, are frequently cracked or broken by sudden strains.

My improvements are readily adapted for broad or narrow gage roads.

Having thus described my invention, what I claim, and desire to secure by Letters Patent, is—

1. An improved combined cross-tie and rail-chair, consisting of the tie A, formed in sections and joined together, said tie formed **H** shape in cross-section, a pillow-block held in the upper socket of the tie and the chair resting upon the pillow-block, and means for securing the block to the tie and the chair to the block, substantially as shown and described.

2. The combination, with the tie A, **H** shape in cross-section, the upper socket h ,

formed dovetailed, of the pillow-block C, formed with a base c, having dovetailed channels c', adapted to fit the dovetail socket h, and the chair E, supported on the pillow-block, and means for securing said chair to the block, substantially as and for the purpose described.

3. The combination, with the cross-tie A, formed with a dovetail socket h, of a pillow-block formed with a dovetail base c, held in

5 said socket, and a rail-chair formed of the base portion having a fixed flange or brace and a movable section or brace, and means for securing said chair to the pillow-block, substantially as and for the purpose described.

MARIAN M. GREEN.
